UNITED STATES PATENT OFFICE.

ELMORE WILLIAMSON, OF NEW ROSS, INDIANA, ASSIGNOR TO HIMSELF
AND GEORGE W. WILLIAMSON, OF SAME PLACE.

IMPROVEMENT IN WINDMILLS.

Specification forming part of Letters Patent No. **177,187**, dated May 9, 1876; application filed
February 11, 1876.

To all whom it may concern:

Be it known that I, ELMORE WILLIAMSON, of New Ross, county of Montgomery, State of Indiana, have invented a new and useful Improvement in Windmills, of which the following is a description, reference being had to the accompanying drawings.

My invention consists of the construction of parts, as fully set forth in the claims hereunto annexed.

Figure 1 represents a perspective view of my improved windmill, showing the general arrangement of parts. Fig. 2 is a sectional view of the governor. Fig. 3 is a perspective view of the socket of the sail-frame. Fig. 4 is a perspective view of the angular support of the sails. Fig. 5 is an enlarged view of the revolving head and its connections.

A A represent the standards, upon which is securely bolted, at the top, the cap B, which has a hole through it to allow the pump-rod F¹ to vibrate in. Above the cap B is arranged a revolving head, D C, which is mounted upon rollers (not shown) between the bottom of C and top of cap B. The upper part of the revolving head C D is formed with a frame, D' D', the upper end of which is provided with a hollow guide, F, and the lower part, C, has a hole through it from bottom to top, in which works the pump-rod F¹. On one side of the frame D' is secured the vane E. On the other side of the frame D' is permanently attached a wrought-iron tube, H², (shown more fully in Fig. 5,) and on the inside of this tube, which is bored out, is fitted the main shaft H¹, which extends through the side frame D', and is provided with a crank-wheel, H. The other end of the shaft H¹ projects beyond the wrought-iron tube H², and is firmly secured in the hub R of the wind-wheel. On the outside of the hollow wrought-iron pipe H² is also fitted the hub M of the governor. This hub is provided at one end with a sheave, O, and at the bottom side with a projecting lug to receive the weight-rod Y, and at the top side is provided with a hinge joint, Q', to which is pivoted, at Q, the upper shaft or arm T of the governor. At the upper end of the shaft T is secured a face-board, U, which is perforated with a large hole, in which is secured, at an angle, the sails V by

means of the casting x², as shown. The sails S are also secured in the same manner to the wind-wheel frame W, which has its braces also secured in the socket x, as shown. The upper shaft or arm T is prevented from falling back or forward by means of the stiff rod T', which is pivoted to the vane E at d, and to the shaft T at f, as shown. The weight Y' at the bottom of the rod Y, holds the face-board in a perpendicular position until the wind becomes too strong, when the face-board V is forced to one side, and at the same time is partially drawn back (as shown in the dotted lines in Fig. 2) by means of the rod T'. This causes the face of the wind-wheel to be moved around at an angle to the wing and prevents the wheel from revolving too fast. The inclination of the face-board is more or less according to the force of the wind, and the motion of the wind-wheel is regulated to a nicety without any jerking motion, as is common with mills formed with adjustable sails. The lower rod Y of the governor is provided with a chain, Y², which is also attached to the revolving head C D, as shown, to prevent the governor or face-board V from being thrown too far on either side. On the side of the revolving head-frame, near the top, is arranged a sheave, L, over which the rope m is carried to the sheave O on the end of the governor-hub M. The other end of the rope m is secured to the clutch F², which is attached to the lower part of the pump-rod F¹. This clutch encircles the sleeve n, which is formed with a square socket that fits the square shaft F¹, and by this means the shaft F can revolve or move around with the wind without changing the position of the clutches F² and F⁵, which are below and connected together by the rods p p. The lower end of the pump-rod F¹ is pivoted to the upper end of the square pump-rod F⁶, between the two clutches F² F⁵, as shown. And the lower clutch F⁵ is also connected with the lever m² by means of the connection m¹. This lever m² is at the bottom of the mill, and is designed to be operated by hand, to throw the wind-wheel out of the wind, by pulling down on the rope m, which passes over the pulleys L and O and operates the governor by pulling the face-board V to one side, thus throwing the wind-

wheel into the wind, so as to stop the mill. The crank H is connected direct with the pump-rod F¹ by means of the pitman J, as shown, and the pump-rod F¹ works in a bearing or hole forward in the lower and upper part of the revolving head C D, and prevents the rod from getting out of line. The sails of the face-board and wind-wheel are secured to the angular screw sockets x² x³, (shown in Fig. 4,) and the braces of the wind-wheel are secured in sockets, as shown in Fig. 3.

What I claim as new, and wish to secure by Letters Patent, is—

1. In combination with the pipe H² and revolving head C D, the hub M of the governor, arranged to operate in the manner shown and described.

2. The hub M, provided with the sheave O at one end, and the hinge-joint Q at the top, as shown and described.

3. The combination of the hub M, rod and weight Y Y¹, and hinged arm T, provided with the face-board U, which is perforated and furnished with the sails V, as shown and described.

4. The sheave L, arranged to operate in connection with the sheave O on the hub M, by means of the rope m and its connections with the lever m², as shown, and for the purposes set forth.

5. The clutch F² provided with the sleeve n, in combination with the clutch F⁶, the pump-rods F¹ F⁶, and rods p p, arranged as shown, for the purposes specified.

6. The socket-casting x, formed, as shown, in connection with the frame of the wind-wheel, as set forth and described.

7. The angular sail-supporting casting x², constructed as shown, and provided with the screw x³ to secure the casting to the wind-wheel or face-board, as set forth and described.

In testimony whereof I have signed my name to this specification in the presence of two subscribing witnesses,

ELMORE WILLIAMSON.
